INVENTOR

Robert S. Shackford.

By his attorney

J. H. J. W. Cready.

UNITED STATES PATENT OFFICE.

ROBERT S. SHACKFORD, OF BROOKLINE, MASSACHUSETTS.

WRENCH.

Application filed March 26, 1920. Serial No. 368,855.

To all whom it may concern:

Be it known that I, ROBERT S. SHACKFORD, a citizen of the United States, residing at Brookline, in the county of Norfolk and 5 State of Massachusetts, have invented certain Improvements in Wrenches, of which the following description, in connection with the accompanying drawings, is a specification, like reference characters on the drawings indicating like parts in the several 10 figures.

This invention relates to wrenches and is especially concerned with wrenches of the type in which a ratchet action may be obtained. The invention has for its chief object to devise a wrench of this type in which a relatively large adjustment of the jaws can be made, which shall be simple in construction, and which can be economically 20 manufactured.

The nature of the invention will be readily understood from the following description when read in connection with the accompanying drawings, and the novel features 25 will be particularly pointed out in the appended claim.

Referring now to the drawings,

Figure 1 is an isometric view of a wrench embodying the invention in the form at 30 present preferred, certain of the parts being broken away for the sake of clearness; and

Fig. 2 is a plan view of the head portion of the wrench shown in Fig. 1 with certain 35 parts broken out.

The construction shown comprises a head consisting of upper and lower plates 2 and 3, respectively, suitably spaced apart and having extensions that cooperate with a 40 spacing block 4 to form the fixed jaw 5 of the wrench. The three parts that make up this jaw are secured together by rivets 6, and the movable jaw 7 of the wrench is made up in the same way as the jaw 5, the 45 parts being riveted together, and an extension or shank 8 projecting from this jaw is slidably mounted in the head to enable the jaw 7 to move in a straight line toward or from the fixed jaw 5. A coiled spring 50 9 mounted in a recess or groove provided in the shank 8 tends to hold the jaws at the innermost limit of their range of relative movement.

For the purpose of moving the jaw 7 both 55 for adjustment and also to clamp it on the

bolt or nut head N on which it is working, the lower edge of the shank 8 is toothed, as shown at 10, and a pawl 11 is mounted in the head in position to engage the teeth 10. The pawl is moved by a handle 12 pivoted 60 on the stud 13 and having a cam shaped projection 14 provided with a socket or seat in which the rounded end of the pawl 11 rests. Another extension 15 of the handle 12 is slotted to receive a pin 16 that also 65 projects through the pawl and through parallel slots in the plates 2 and 3, the slot in the plate 3 being shown at 17. Normally the pawl 11 is held in engagement with the teeth 10 by a spring 18.

It will now be seen that when the handle 12 is swung in a clockwise direction about the pivot 13 the cam piece 14 acting on the end of the pawl 18 will slide this pawl toward the right, and through the engagement of the pawl with the teeth 10 this force will be transmitted to the jaw 7 thus closing the jaws on the work. When the handle is swung in the opposite direction to turn the wrench into position to secure 80 another "bite" on the work, the walls of the slot in the extension 15 act on the pin 16 to slide the pawl 18 toward the left thus releasing the grip of the jaws on the work and enabling the movable jaw to slide backwardly as it passes around the corners of the nut or bolt head on which the wrench is 85 working. As soon, however, as the wrench has been moved far enough to secure its new "bite" and the handle is again swung 90 in a clockwise direction, the operation above described will be repeated to cause the jaws to firmly grip the work. It will be seen that the tip 20 of the pawl 11 projects from between the plates 2 and 3 far enough to enable it to be grasped by the workman and released from the teeth 10 to permit the 95 manual adjustment of the jaw 7. Such an adjustment, however, does not interfere with the ratcheting action. A spacing stud 21 cooperates with the stud 13 to hold the plates 2 and 3 in their properly spaced relationship.

It will now be evident that the invention provides a relatively simple construction of 105 wrench in which a relatively large adjustment of the jaws can be made without affecting the ratcheting action. Furthermore, since the more important parts of the wrench can be made from sheet metal punch- 110

ings or stampings, it will be seen that it can be manufactured very economically.

While I have herein shown and described the best embodiment of the invention of 5 which I am at present aware, it will be understood that this embodiment may be modified in many particulars without departing from the spirit or scope of this invention.

10 What is claimed as new is:

A wrench of the character described, comprising a hollow head, a jaw rigid therewith, a movable jaw having a toothed shank portion mounted in said head to enable said 15 movable jaw to slide toward and from the

fixed jaw, a spring tending to move said movable jaw into its closed position, a handle pivoted in said head, a pawl mounted in said head to engage the teeth of said shank, a pin and slot connection between said pawl and said handle for moving said pawl in one direction, a cam connection between said pawl and said handle for moving the pawl in the opposite direction to close said jaws, and a spring for holding said pawl in engagement with the teeth on the shank of said movable jaw.

In testimony whereof I have signed my name to this specification.

ROBERT S. SHACKFORD.
